UNITED STATES PATENT OFFICE.

ROBERT B. GRIFFIN, OF NEW YORK, N. Y.

DESIGN FOR WALL-PAPER.

50,570.

Specification for Design.

Patented Apr. 10, 1917.

Application filed January 26, 1917. Serial No. 144,788. Term of patent 7 years.

To all whom it may concern:

Be it known that I, ROBERT B. GRIFFIN, a citizen of the United States, residing at New York, in the county and State of New York, have invented a new, original, and ornamental Design for Wall-Paper, of which the following is a specification, reference being had to the accompanying drawing, forming a part thereof.

The figure is a plan view of a piece of wall paper, illustrating my new design.

I claim:—

The ornamental design for wall paper, substantially as shown.

In testimony whereof I hereunto affix my signature.

ROBERT B. GRIFFIN.
